UNITED STATES PATENT OFFICE.

JOHN V. B. CARTER, OF ROCHESTER, NEW YORK, ASSIGNOR TO THE CO-OPERATIVE FOUNDRY COMPANY, OF SAME PLACE.

DESIGN FOR A HEATING-STOVE.

SPECIFICATION forming part of Design No. 16,805, dated July 20, 1886.

Application filed May 14, 1886. Serial No. 302,208. Term of patent 7 years.

To all whom it may concern:

Be it known that I, JOHN V. B. CARTER, a citizen of the United States, residing at Rochester, in the county of Monroe, in the State of New York, have invented and produced a new and original Design for Stoves, of which the following is a specification, reference being had to the accompanying photograph, forming part hereof.

10 The accompanying photograph represents my design for stoves.

The stove embodying my design consists, substantially, of the base or skirt section A, the ash-pit section B, and the magazine-section C, all of which are rectangular with truncated corners, and the top or upper section, D, of oval shape, surmounting the magazine-section. Above the top section is placed the cover E, of an oval dome-shaped form, on which rests 20 an ornamental figure of a knight on horseback, F, carrying a shield, j, displaying a cross. The lower margin of the cover E is provided with a broad smooth band, a, having a row of vertical indentations, b, in its surface, while 25 the upper portion of the dome is ornamented with raised work of substantially the character represented at c. The top section, D, is surrounded at its upper edge by an outwardly-projecting molding or cornice, d, of an oval 30 form, corresponding with that of the section, and having its upper surface rounded or curved inwardly, as shown at e, to meet the bottom of the cover. At the center of its front the top section is provided with the 35 medallion f, and at each side with the circular tile ornament or rosette g. Between the medallion and the ornament g the vertical surface of the top section is ornamented with one or more raised scrolls, h, with a representation 40 of a flower and other leaf-work, substantially as shown. It will be observed that the top section is of somewhat smaller dimensions than the lower parts of the stove. Around the bottom of the top section, where it joins 45 the upper plate, G, of the magazine-section, is placed the curved molding i, forming the base of the top or dome section. The plate G, which connects the top section with the magazine-section, is provided with a curved flange, k, 50 projecting somewhat beyond the walls of the

magazine-section, but of the same general form as seen from above, with truncated corners l. At the front and rear sides of the stove the projecting flange k is curved or bent upward nearly to the bottom of the top section in a 55 graceful form, as shown at m. The edges of the flange k are preferably inclined slightly, as indicated, or they may be vertical. Inside the flange the upper surface of the plate G is rounded or curved upward and inward, so as to meet the molding i, being ornamented with 60 raised scroll-work, as shown at n, and having the raised rounded ornaments o at the corners, displaying a cross which is sunken. As already stated, the magazine-section C is rectangular in form, with truncated corners and parallel vertical sides. It is provided in front with the double doors p p', and at the sides with the doors q q', all of which are fitted with 65 mica lights. At the corners of the magazine or combustion section C the stove is provided with the mica light or lights represented at r, below which is the raised panel s, having a female head thereon surrounded with ornamental scroll-work, as shown. The doors p p' 70 are provided with vertical and horizontal bars, as shown, the rounded surface of which is ornamented in imitation of rustic work. The posts or pillars t at each side of the truncated corners of the magazine-section are ornamented 75 with raised work, as represented in the photograph. The ash-pit section B is provided around its upper end with the flange u, the sides of which are inclined inward slightly, with a rounded molding at their upper edges. 80 The truncated corners of the ash-pit section are ornamented with bust of a knight in armor, as shown at v. In front suitable ornamental arms attached to the door support the foot-rest H, while at the sides the foot-rests I and 85 J are supported from the ash-pit section by the arms w, having curved ribs x x, ornamented on their inner edges, as shown, and having a circle with an interior cross, as represented at y. The base A is ornamented in front with the 90 medallion z, and at the sides with the rosette or circular piece a', in keeping with the corresponding ornamentation, f and g, on the top section. The feet L of the stove project upward outside of the truncated corners of the 95 100

base, being ornamented, as shown, to represent a collection of leaves. The lower ends of the feet *L* are representations of the claws of an animal, as shown. The base is ornamented further by the straight and curved moldings *b'* and the representation of the flowers *c'*.

The front doors are surmounted by a center ornament consisting of a female head with leaf or flower work extending each way therefrom.

10 I do not claim the design for the knight on horseback herein shown, as the said design was not originated by me.

I claim—

15 1. The design for a heating-stove, consisting of the sections *A*, *B*, *C*, and *D*, with plate *G*, having the shape and ornamentation herein shown.

20 2. The design for the upper portion of a heating-stove, consisting of the oval top section, *D*, surrounded at its upper edge by the cor-

nice *d*, and provided at the center of its front with the medallion *f*, and on each side with the circular rosettes *g*, and the intermediate raised scroll-work, *h*, substantially as herein shown.

25

3. In a design for a stove, the design for the base-section *A*, consisting of the medallion *z* at the center of the front, the rosettes *a'* at each side, the straight and curved moldings *b'*, and flowers *c'*, substantially as shown.

30

4. In a design for a stove, the feet *L*, consisting of a group of leaves projecting above the outside of the truncated corners of the base, and having claws at their lower ends, substantially as shown.
